UNITED STATES PATENT OFFICE

158,985

SANITARY BOWL OR THE LIKE

Pearl B. Lorenzen, Toledo, Ohio, assignor to The Urikit Co., Toledo, Ohio, a corporation of Ohio

Application February 1, 1949, Serial No. 614

Term of patent 14 years

(Cl. D44—10)

To all whom it may concern:

Be it known that I, Pearl B. Lorenzen, a citizen of the United States of America, residing at Toledo, Lucas County, Ohio, have invented a new, original, and ornamental Design for Sanitary Bowls or the like, of which the following is a specification, reference being had to the accompanying drawings, forming part hereof.

Fig. 1 is a plan view of a sanitary bowl or the like, showing my new design;

Fig. 2 is a side elevational view; and

Fig. 3 is an end elevational view thereof.

I claim:

The ornamental design for a sanitary bowl or the like, as shown.

PEARL B. LORENZEN.
